(57) **CLAIM**

The ornamental design for a printer, as shown and described.

DESCRIPTION

FIG. 1 is a front, left, top, perspective view of a printer showing our new design;

FIG. 2 is a front, right, top, perspective view of the printer shown in FIG. 1;

FIG. 3 is a front elevational view of the printer shown in FIG. 1;

FIG. 4 is a rear elevational view of the printer shown in FIG. 1;

FIG. 5 is a left-side elevational view of the printer shown in FIG. 1;

FIG. 6 is a right-side elevational view of the printer or shown in FIG. 1;

FIG. 7 is a top plan view of the printer shown in FIG. 1; and, FIG. 8 is a bottom plan view of the printer shown in FIG. 1. The broken lines shown in the drawings represent portions of the printer that form no part of the claimed design.

1 Claim, 8 Drawing Sheets
